UNITED STATES PATENT OFFICE

162,994

CHILD'S APRON IN THE FORM OF A PUPPET

Hortense Savron, New York, N. Y.

Application February 10, 1951, Serial No. 14,178

Term of patent 7 years

(Cl. D3—26)

To all whom it may concern:

Be it known that I, Hortense Savron, a citizen of the United States, residing in the county of Bronx, city and State of New York, have invented a new, original, and ornamental Design for Child's Apron in the Form of a Puppet, of which the following is a specification, reference being had to the accompanying drawing, forming a part thereof.

Fig. 1 is a perspective view of a child's apron in the form of a puppet, showing my new design; and

Fig. 2 is a side elevational view thereof as seen from the right hand side of Fig. 1, showing the straps broken away for the purpose of illustration.

I claim:

The ornamental design for a child's apron in the form of a puppet, as shown and described.

HORTENSE SAVRON.
